UNITED STATES PATENT OFFICE

GORDON WILLIAMS, OF MOUNT CARMEL, CONNECTICUT

HOOD FASTENER FOR AUTOMOBILES

Application filed October 11, 1927. Serial No. 225,475.

This invention relates to improvements in hood fasteners for automobiles. In the more general construction, two or more separate fastening devices are employed for locking each side of the hood of an automobile, and to unlock and lift the hood, it is first necessary to disconnect the locking devices and then raise the hood. Means have been provided for releasing two or more locking devices at one operation, but in such constructions springs have been employed and springs are objectionable as they tend to permit parts to rattle.

The object of this invention is to provide a locking device by which the hood will be firmly locked in position, and by a single movement or operation the hood may be unlocked and raised.

A further object of the invention is to provide means for adjusting the parts to compensate for varying conditions or positions, and the invention consists in the construction as hereinafter described and particularly recited in the claims.

In the accompanying drawings:

Fig. 1 is a side view of an automobile hood having locking means constructed in accordance with my invention;

Fig. 2 is a broken inside view of the same on an enlarged scale;

Fig. 3 is an end view illustrating the locking mechanism;

Fig. 4 is a sectional view on the line 4—4 of Fig. 3;

Fig. 5 is a sectional view on the line 5—5 of Fig. 3;

Fig. 6 is a sectional view on the line 6—6 of Fig. 2;

Fig. 7 is a perspective view of one of the yoke-plates detached;

Fig. 8 is a perspective view of one of the yokes detached;

Fig. 9 is a perspective view of one of the latches detached; and

Fig. 10 is a perspective view of one of the shaft-bushings detached.

In carrying out my invention, I employ a rock-shaft 15, angular in cross-section, and extending through bushings 16 which are mounted in brackets 17 secured to the inner

face of the movable part 18 of an automobile hood. Coupled with the shaft 15, preferably near the center thereof, is an operating-lever 19 which projects outward through a slot 42 in the hood 18, the said lever 19 being 55 formed with a grip 20 and preferably with a finger-opening 21. Connected with the bushings 16, so as to turn therewith, are latches 22 having cam-hooks 23 and a locking-notch 24. Mounted on the chassis 25 in 60 line with the latches 22 are yokes 26, and these yokes are preferably mounted on screw-studs 27, being locked throughout by nuts 28 and 29. Preferably, the screw-studs 27 will be formed with a longitudinal groove 65 30, and an opening 31 in the yoke, to set over the stud, will be formed with an inwardly-projecting lug 32, whereby the yoke is held against turning. Pivotedly secured to the arms 33—34 of the yokes are plates 35—36, 70 and mounted in the upper ends of these plates is a transverse pin 37 adapted to be engaged by the latch 22. Preferably one of the plates, as 36, is formed at its lower end, below the pivot 38, with an outward bend 75 39 to be engaged by a screw 40 entering an extension 41 on the yoke, whereby the plates may be rocked to bring the pins 37 into proper position with relation to the latches.

The parts being properly adjusted and the 80 movable part of the hood closed, a downward pressure on the operating-lever forces the latches into engagement with the pins 37 and, owing to the cam-hooks 23, the hood is drawn inward and downward and the pin resting in 85 the notch 24 cannot become loose, and hence the hood is firmly locked in position. To open the hood, an upward movement is given to the lever 19, and this movement is assisted by passing one finger through the hole 21, 90 thus rocking the shaft 15 and turning the latches out of engagement with the pins 37 and thus disengaging the hood, so that a continued upward movement on the lever will 95 raise the movable part of the hood. In case one of the latches does not engage with sufficient tension upon its complementary pin, the plates 35—36 may be adjusted by the screw 40 so as to bring the pins into proper alignment, and, if necessary, the yoke may 100

be adjusted upon the screw-stud 37 to provide for variation in position, but when once adjusted for any particular place, the parts are not liable to become deranged and further adjustment will seldom be necessary.

5 I thus provide, in a very simple and effective way, means for locking or unlocking the movable part of an automobile hood by a single operation, so that the hood can be readily 10 unlocked and lifted with one hand, and as no springs are employed, the parts are not liable, nor is it possible for them, to become accidentally detached.

I claim:

15 1. In a hood fastening for automobiles, the combination with the hood of a rock-shaft mounted on the inner face thereof, a lever coupled with said shaft and extending outward through said hood and provided with 20 a handle, latches coupled with said shaft near the ends thereof, said latches formed with cam-faces and with locking-notches, yokes mounted on the chassis in line with said latches, plates secured to said yoke and extending upward therefrom, and pins mounted 25 in the upper ends of said plates and in position to be engaged by said latches.

2. In a hood fastening for automobiles, the combination with the hood of a rock-shaft 30 mounted on the inner face thereof, a lever coupled with said shaft and extending outward through said hood and provided with a handle, latches coupled with said shaft near the ends thereof, said latches formed with 35 cam-faces and with locking-notches, yokes mounted on the chassis in line with said latches, plates secured to said yoke and extending upward therefrom, pins mounted in the upper ends of said plates and in position 40 to be engaged by said latches, and means for adjusting the position of said plates with relation to the yoke.

3. In a hood fastening for automobiles, the combination with the hood of a rock-shaft 45 mounted on the inner face thereof, a lever coupled with said shaft and extending outward through said hood and provided with a handle, latches coupled with said shaft near the ends thereof, said latches formed with 50 cam-faces and with locking-notches, yokes mounted on the chassis in line with said latches, plates secured to said yoke and extending upward therefrom, pins mounted in the upper ends of said plates and in position 55 to be engaged by said latches, means for adjusting the position of said plates with relation to the yoke, and means for vertically adjusting the said yokes.

In testimony whereof, I have signed this 60 specification.

GORDON WILLIAMS.
